UNITED STATES PATENT OFFICE.

JONAS JOHNSON, OF RAMSAY, MICHIGAN.

POCKETKNIFE.

1,422,363.

Specification of Letters Patent.

Patented July 11, 1922.

Application filed March 24, 1920. Serial No. 368,287.

To all whom it may concern:

Be it known that I, JONAS JOHNSON, a citizen of the United States, and a resident of Ramsay, in the county of Gogebic and State of Michigan, have invented certain new and useful Improvements in Pocket-knives, of which the following is a specification.

My invention is an improvement in pocket knives, and has for its object to provide a knife of the character specified wherein a handle is provided, consisting of a sheath, and having means therein for engaging interchangeable tools, as, for instance, cutting blades, screw drivers and the like, and for holding said tools firmly in place either within the sheath or extended therefrom in position for use.

In the drawings:

Figure 1 is a top plan view of the improved knife, with the blade extended;

Figure 2 is a similar view, with the sheath removed;

Figures 3 and 4 are sections on the lines 3—3 and 4—4, respectively, of Figure 2;

Figure 5 is a plan view of the knife, with the blade in the sheath;

Figure 6 is an end view;

Figure 7 is a section on the line 7—7 of Figure 6.

In the present embodiment of the invention there is provided a sheath or case 1, which is in the form of a tubular structure having open ends and having one end reduced slightly, as shown at 2. Within this sheath or case, which is adapted to hold a series of tools, such as blades, there is arranged a yoke or substantially U shaped member, consisting of a bight portion 3 and arms 4 extending laterally from the bight, the said yoke being of resilient material.

A series of interchangeable tools is adapted for use with the handle composed of the sheath and the yoke, each of the said tools, one of which is shown, being composed of a blade portion 5 and a tang or shank 6. Each of the arms of the yoke is provided at its free end with an internal enlargement 7, which is grooved on its inner face as indicated at 8. The opposite side edges of the shank portion of the blade are correspondingly beveled, as clearly shown in Figure 4, to engage in these grooves, and the tang or shank of each tool has outwardly extending pins or lugs 9 at its op-

posite side edges, and intermediate the ends of the shank portion, which are adapted to engage openings 10 in the arms 4 at the enlargements 7. Thus the tool is held from movement longitudinally of the handle, as well as from lateral movement or twisting movement, and there is sufficient resiliency in the yoke to insure a firm grip on the tool.

Each arm 4 of the yoke has an outwardly extending lug 11 at its free end and these lugs are adapted to abut the sheath at the adjacent end thereof, as shown in Figures 1 and 5, to hold the arms 4 firmly clamped on the shank of the tool. Releasable means is provided for preventing accidental outward movement of the yoke with respect to the sheath, that is, the movement of the yoke toward the blade holding end of the device. The said mechanism is in the form of a spring latch 12 which at one end is secured within the sheath as at 13, and has at the other end an angular portion 14 which is adapted to engage within one of a series of transverse notches 15 in the inner face of the bight portion of the yoke. As shown, a portion of the spring plate 12 at the angular portion 14 is bent upwardly and outwardly to provide a fingerpiece 16 for convenience in manipulating the latch.

When not in use the tool, which may be of various forms, as, for instance, blades, screw drivers, files and the like, is held within the sheath, as indicated in dotted lines in Figure 2.

When it is desired to insert a blade in the handle for use, the latch 12 is pushed laterally, as indicated by the dotted lines in Figure 1, until in register with a notch 17 in the bight 3 which is of sufficient depth to permit the passage of the latch when the yoke is moved forwardly. Each face of the bight portion of the yoke has a notch 17 so that whichever way the yoke is turned the latch may release. The yoke is pushed and pulled from the case and a blade is inserted between the arms thereof, the pins 9 of the blade engaging the openings 10 of the yoke. The yoke, with the blade in the full line position of Figure 2, is then reinserted in the sheath and is pushed inwardly until the lugs 11 abut in the end of the sheath.

When now the latch 12 is swung laterally, as indicated in Figure 1, the angular end thereof will engage one of the notches 15.

of the yoke and will hold the yoke from movement within the sheath toward the blade holding end. In order to interchange a tool, it is only necessary to withdraw the 5 yoke from the sheath, take out the old blade, insert a new one, return the yoke to the sheath, and the tool is ready for operation.

In order to change a tool from the full 10 line position of Figure 2 to the broken line position of the said figure, it is not necessary to entirely release the pins 9 from the openings 10. After the yoke has been removed from the sheath, the tool may be 15 reversed merely by swinging it toward the dotted line position of Figure 2. This movement of the tool spreads the arms, but sufficient engagement remains between the pins and the openings 10 to prevent disengagement of the tool from the yoke.

20 I claim:

1. A device of the character specified comprising a yoke or substantially U-shaped member and interchangeable tools, each having at one end a shank whose opposite side edges are beveled, the yoke comprising a bight portion and arms diverging therefrom, and each arm having on its inner face at its free end a groove for engaging the adjacent beveled edge of the shank, the shank of the 25 tool having outwardly extending pins intermediate the ends of the beveled edges, and the grooved ends of the yoke arms having aligned openings for engagement by said pins, means for clamping the yoke arms on the shank, said means comprising a flattened tubular sheath into which the bight end of the yoke is adapted to pass, the free 30 ends of the yoke arms having oppositely extending lateral lugs to engage the end of the sheath to firmly clamp the grooved ends of the arms on the shank, and releasable means for locking the yoke in the sheath and to permit its withdrawal.

2. A device of the character specified, 45 comprising a substantially U-shaped yoke member, and interchangeable tools, each having at one end a tang or shank whose opposite side edges are beveled, the yoke member comprising a bight portion and arms diverging therefrom and resilient, each arm having on its inner face at its free end a groove for engaging the adjacent beveled edge of the shank, said shank having outwardly extending pins intermediate the ends 50 of the beveled edges, the yoke arms having openings for engagement by the pins, and means for clamping the yoke arms on the shank, said means including a flat tubular casing into which the bight end of the 55 yoke member is passed, the yoke arms hav-

ing outwardly extending lugs at their ends to engage the casing to firmly clamp the arms on the shank and to prevent the tool sliding into the casing while in use.

3. A device of the character specified comprising a yoke or substantially U-shaped member and interchangeable tools each having at one end a shank whose opposite side edges are beveled, the yoke comprising a bight portion and arms diverging therefrom 65 and from each other and resilient, each arm having on its inner face at its free end a groove for engaging the adjacent beveled edge of the shank, the shank of the tool having outwardly extending pins intermediate 70 the ends of the beveled edges, and the yoke arms having openings for engagement by the pins, and means for clamping the yoke arms on the shank, said means comprising a sheath into which the yoke is adapted to 75 pass, said sheath enclosing the yoke.

4. A device of the character specified comprising a substantially U-shaped member, and a blade having at one end a shank, said U-shaped member comprising a bight portion and resilient arms adapted to engage opposite edges of the shank, said shank and arms having interengaging means for pivotally connecting the blade to the arms and releasable by movement of the arms away 80 from the shank, said arms being grooved on their inner faces to receive opposite edges of the shank for the purpose specified, and a sheath for receiving the U-shaped member and for holding the arms closed on the 85 blade, said sheath having releasable means adapted to hold the yoke within the sheath and also to permit the releasing of the U-shaped member from the sheath.

5. A device of the character specified comprising a substantially U-shaped yoke member including a bight portion and arms resiliently diverging therefrom, interchangeable tool members, each having at one end a tang or shank the opposite side edges of 100 which are beveled, the inner face of the free ends of the resilient arms correspondingly grooved for engaging said beveled edges, the tang of the tool having outwardly extending pins projecting from the beveled edges, the 105 grooved free ends of the arms having transverse sockets to receive said pins, means for maintaining the yoke, arms and tang in interlocked relation, said means comprising a tubular sheath, and a movable latch mounted within the sheath and adapted to abut the said bight portion of the yoke to retain the same within the sheath and also to permit its removal therefrom.

JONAS JOHNSON.
